UNITED STATES PATENT OFFICE

140,871

DESIGN FOR A CLUSTER RING OR SIMILAR ARTICLE

Edward N. Schenkein, New York, N. Y.

Application January 3, 1945, Serial No. 117,232

Term of patent 7 years

(Cl. D45—10)

To all whom it may concern:

Be it known that I, Edward N. Schenkein, a citizen of the United States, residing in New York city, in the county of New York and State of New York, have invented a new, original, and ornamental Design for a Cluster Ring or Similar Article, of which the following is a specification, reference being had to the accompanying drawing, forming part thereof.

Fig. 1 is a top view of a cluster ring or similar article showing my new design, and
Fig. 2 is a side elevational view thereof.

I claim:

The ornamental design for a cluster ring or similar article, substantially as shown.

EDWARD N. SCHENKEIN.
